NOVELTY UTILITY ARTICLE

Kathrine Beck Rollins and Mark L. Rollins,
Valley Stream, N. Y.

Application March 31, 1952, Serial No. 279,564

10 1 Claim. (Cl. 211—11)

This invention relates to improvements in novelty 15 utility articles providing receptacle means and the like.

An object of the invention is to provide a novel and improved novelty utility article having a number of walls defining individual compartments for the reception of goods, stationery merchandise, mail and the like.

Another object of the invention is to provide a novel and improved novelty utility article in which there are pairs of walls interconnected by spacing webs to form substantially upwardly open receptacle compartments, each adjacent pair of said walls being in turn interconnected at upper edges by integrating webs to define a continuous series of combined cooperative receptacle compartments.

A further object of the invention is to provide a novel and improved novelty utility article in which there is a plurality of upstanding walls, each wall spaced from adjacent walls, alternate walls being interconnected at the bottom by integrating webs, or at the top, to form an undulating assembly defining a series of alternating upwardly open receptacle recesses for the reception of articles, mail, and the like, with shelf means extending from selected walls for supporting discrete articles and the like thereon.

Still another object of the invention is to provide a novel utility article of the type described, in which longitudinal leg means is secured to all the lower interconnecting webs and providing means upon which said article is both supported and may be moved slidably over any supporting surface.

Still a further object of the invention is to provide a novel utility article of the type described, which is formed of a single main sheet of material with a series of major upstanding corrugations and undulations along its length, defining a series of upwardly open receptacle recesses having smoothly contoured walls, forward and rearward upper marginal portions of the first and last of said corrugations forming lip-like shelves for the support of discrete articles, and/or time indicating means.

Another object of the invention is to provide a novel utility article of the type described, in which said major assembly of continuous undulations is supported on a support assembly comprising frame and drawer means, the drawer means being slidably retractable to afford access to the interior thereof.

A further object of the invention is to provide a novelty utility article of the type described, which is simple in design, inexpensive to manufacture, attractive in appearance, and highly effective for its intended purposes.

These and other objects and advantages of the invention will become apparent from the following description of a preferred embodiment thereof as illustrated in the accompanying illustrations, forming a part hereof, and in which,

Figure 1 is a perspective view showing a preferred form of the invention, with two compartments.

Figure 2 is a right end elevational view of the device shown in Figure 1, as seen on plane 2—2 of Figure 1.

2

Figure 3 is a perspective view showing another modified form of the invention, with several compartments.

Figure 4 is a view similar to that of Figure 2, but showing a modified form of the invention.

Figure 5 is a perspective view showing another modified form of the invention.

In the manufacture and use of novelty utility articles various considerations must predominate, depending upon the desires of the manufacturer and the ultimate consumer or user thereof. Where, for example, incoming mail is to be sorted and arranged in accordance with any desired pattern of the user, it is important that such sorting means be simple and convenient and at the same time constructed so as to be attractive in appearance while retaining its full utilitarian purposes and facilities. The present invention discloses such a novelty utility article, which is quite attractive in appearance, yet is so constructed that not a whit is subtracted from its appearance in the course of providing for full utilitarian objectives. It not only permits sorting of any generally planar articles and objects, not restricted to mail alone, in one or more discrete and plainly visible compartments, but also, as desired, may provide for the storage of other articles in a novel manner.

In order to understand clearly the nature of the invention, and the best means for carrying it out, reference may now be had to the drawings, in which like numerals denote similar parts throughout the several views.

As seen best in Figures 1 and 2, there is a major assembly generally indicated at 10, which has a first upstanding wall 12, which may be formed of sheet material of suitable rigidity or stiffness, such as plastic, metal, compositions, or other materials, and has an upper edge 14 bounded by vertical side edges 16 and 18, and terminating in its lower marginal portion 20 in a curved web 22, preferably integrated with front wall 12. A second wall 24 is spaced from the first wall 12, and may be substantially parallel thereto as seen in Figure 2, or curved somewhat relative thereto, as seen in Figure 4.

The upper edge 26 of the second wall 24 is smoothly preferably integrated with a curved web 28, which then integrates downwardly with the upper marginal edge 30 of the third wall 32, which in the form shown in Figures 1 and 2 is substantially parallel to walls 18 and 24. However, as seen in Figure 4, such wall 32a may be smoothly curved somewhat as shown. The lower marginal portion 38 of the wall 32 is smoothly integrated with the curved web 40 which then turns upwardly smoothly for integration with the fourth wall 42, which again is shown in Figures 1 and 2 as planar.

Ball feet 44, 45, 48 and 50, formed of the same material as the walls 18, 24, 32 and 42, may be secured to the curved webs 22 and 40 of the device shown in Figures 1 and 2, by means of cement, adhesives, or other fastening means, or may be cast integral therewith. The lower portions of the ball feet are all brought into a common plane, so that they will all make equal contact with a table top or other supporting surface when the device is placed thereon. When in use, it is seen that the device may be placed on a table top with its ball feet resting thereon, as in Figures 1 and 2, or with its curved webs 22a and 40a resting thereon as in Figure 4 in case the balls such as 44 are omitted.

A pair of compartments or receptacles 52 and 54 are thus formed, which are not only upwardly open, but also open at each end, and mail, envelopes, stationery, or the like may be disposed therein, as at 60, resting on the walls 24 and 42 in the manner shown, and on the webs 22 and 40. By making the walls plastic and transparent, it is easy to see at a glance just what mail has arrived, and the user may also make suitable identifying nota-

tions thereon, as for example, the notation "MAIL" on the wall 12, and "Mr. John Doe," and the notation "Mrs. John Doe" being shown on the second wall 42, on the upper margin thereon. By sloping the walls and curving them somewhat, as seen in Figure 4, the appearance is somewhat enhanced, and in addition, the envelopes may be arranged to incline somewhat more toward the rear for increased stability.

Referring now to Figure 3, it is seen that there is a plurality of such walls 18b, 24b, 32b, 42b, etc., which correspond generally to the construction shown in Figures 1 and 2. However it is seen that there are more than two compartments, the number of compartments being increased by the addition of integrated upstanding walls 62, 64, 66, and 68, with curved webs 70, 72 and 74 interconnecting them as shown. Further it is seen that there are tubular cylindrical runners or legs 76 and 78 secured to all the lower end webs 22b, 40b, 70 and 74, either by molding, adhesively, or otherwise, maintaining them in rigid array. The runners 76 and 78 are substantially parallel as shown, and their lower edges lie in a common plane, so that they will not scratch or mar the table top on which they rest.

At the same time, they are hollow cylinders, and may have various articles, such as pencils, pens and the like, inserted through their open ends for ready use when needed. The front wall 12b has its upper margin bent smoothly forwardly as at 80, and thence downwardly as at 82 and upwardly as at 84, to form a trough 86 to receive small articles, pencils, paper clips, and the like 88. At the same time, the rear wall 68 may have its upper margin 90 upturned and then downturned as at 92, and thence formed into a planar trough bottom 94, with upturned lip 96, terminating in an upstanding wall portion 98, containing a clock 100. The trough 94 may be employed to hold suitable implements 102, pencils, pens and the like as needed.

Referring now to Figure 5, it is seen that there is a bottom assembly 104 formed in the general shape of a box, with top wall 106, back wall 108, bottom wall 110, and side walls 114 and 116, with front wall 118 secured thereto. An opening is formed in the front wall 118, to receive a sliding drawer 120 with pull knob 122, which is retractable to afford access to its interior for storage of articles, clips, and the like. Mounted on the bottom assembly 104, and secured thereto in any suitable manner, as adhesively, molding integrally therewith, or by fastening means, is shown the two compartment unitary assembly of a type similar to that shown in Figures 1, 2 and 4. However, instead of using the ball feet like 44,

of Figures 1 and 2, or the tubular runners like 76 in Figure 3, we employ the bottom drawer assembly 104 for this purpose, lending weight and stability thereto, and providing additional utility features. The upper compartmented portion of the unit may have the walls 12c, 24c, 42c, etc., corresponding to the similarly numbered walls and construction of Figures 1, 2 and 4, and or may be formed like the walled assembly of Figure 3, omitting however, the runners 76 and 78.

Although we have described our invention in specific terms, it will be understood that various changes may be made in size, shape, materials and arrangement without departing from the spirit and scope of the invention as claimed.

We claim:

A novelty utility rack consisting of a plurality of mutually spaced main compartment walls all of which are mutually parallel and formed of rigid sheet material, curved floor web walls integral with and interconnecting lower portions of adjacent main compartment walls to form successive upwardly open compartments, curved top web walls integral with and interconnecting upper portions of adjacent main compartment walls of successive compartments to form an undulating upwardly open serially successive plurality of spaced compartments integral with each other, a pair of hollow tubular support runners disposed in mutually parallel array below said floor web walls and secured thereto for supporting the same, a first integral shallow rack lip trough carried by one of said main compartment walls at its upper end for supporting articles, a second integral shallow rack lip trough carried by another of said main compartment walls at its upper end for supporting articles, said first and second rack lip troughs being carried by main compartment walls at opposite ends of said utility rack so as to extend in opposite directions outwardly therefrom, and an upstanding stub wall integral with said second rack lip trough with a socket formed in said stub wall and adapted for supporting articles seated in said socket.
